DRAINAGE VALVE

Edward W. Anger, Chicago, Ill.

Application November 27, 1931, Serial No. 577,520

6 Claims. (Cl. 303—88)

This invention relates to drainage valves for fluid pressure systems and has special reference to drainage valves for draining liquid from fluid pressure systems with substantially no reduction of pressure therein.

More particularly this invention relates to automatic, intermittent acting drainage valves for draining liquids, such as water, oils, and the like, from fluid pressure systems of the type commonly used on electric railway cars. The drainage valve is adapted to be attached to the bottom of the main reservoir of the pressure system or wherever liquids may collect.

This valve comprises a valve casing having an inlet and an outlet with valve members arranged to open and close the inlet and outlet alternately. Thus the liquid which collects within the pressure system may escape into the drainage valve which is closed to the outer air, and when the drainage valve inlet is closed the outlet is opened to permit the water in the drainage valve to escape without affecting the pressure in the pressure system.

In fluid pressure systems, a liquid, comprising mostly water, collects within the system, due to condensation of the moisture in the fluids. When this liquid is not frequently drained, it rapidly accumulates, decreasing the storage space in the reservoir and interfering with the operation of the system as a whole.

Furthermore, when the system is exposed to low temperatures, the liquid therein may freeze and impair the operation of the system. A small amount of liquid collecting within the system will not ordinarily freeze as the compressed air or other fluid gives off sufficient heat to prevent this, but when the amount of liquid increases, the compressed air can no longer prevent it from freezing. It is therefore desirable to drain the liquids frequently.

While the present invention will be hereinafter described in connection with a compressed air brake system of the type commonly employed on electric railway cars, it is to be understood that it is applicable to any fluid pressure system.

An object of the present invention is to provide a drainage valve for draining the collected liquid from a fluid pressure system with substantially no reduction of pressure in the system.

Another object is to provide a drainage valve of the above referred to type which is automatically controlled for draining the liquid which collects within the system at frequent intervals.

Still another object is to provide a drainage valve having a heating element therein to prevent freezing of the liquid within the valve.

A still further object is to provide a drainage valve which is automatically controlled either electrically or by pressure or by a combination of the two.

Further objects will be apparent from the following description when taken in conjunction with the accompanying drawings, in which latter:

Fig. 1 is a diagrammatic view of a fluid pressure system with a pressure and electrically controlled drainage valve connected thereto;

Fig. 2 is a diagrammatic view of a fluid pressure system with an electrically controlled valve connected thereto;

Fig. 3 is a cross-sectional view of one form of electrically controlled drainage valve embodying the present invention, attached to a reservoir in a fluid pressure system;

Fig. 4 is a cross-sectional view of another form of valve controlled by a solenoid and by pressure, attached to a reservoir in a fluid pressure system;

Fig. 5 is a cross-sectional view of still another form of drainage valve which is spring-closed and pressure-opened; and

Fig. 6 is a cross-sectional view of a still further form of drainage valve which is spring and pressure-closed and is opened by a solenoid.

Referring to the drawings and, particularly, to Fig. 1, there is shown in diagram a typical compressed air system for electric cars, comprising an electric motor operated air compressor 1 of usual or desired type, connected to the main air pressure reservoir 3 by an intake pipe 2. The operation of the compressor is automatically controlled by a governor switch 4 suitably connected to the main reservoir 3 and which opens and closes its electric switch 5 in the branch circuit 6 from the main trolley circuit, when the pressure in the reservoir rises or falls beyond predetermined limits. A pipe 7 connects the main reservoir to the motorman's valve 8, which controls the air pressure in the brake cylinder 9. The brake cylinder 9 is connected to the motorman's valve by the straight air application pipe 10 and a pipe section 11. Another pipe 12 connects the pressure chamber of the valve 13 to the straight air application pipe 10 so that whenever pressure is applied to the brake cylinder 9, it is also applied to the pressure chamber in the valve 13. The electric solenoid in the valve casing which also serves to control the valve 13, is connected to the wire 14 which supplies the electricity for operating the compressor 1 by branch 15. A fuse 16 is placed in the line 15 so that if anything goes wrong with the electric circuit connected to the drainage valve, it will not effect in any way the pressure or electric system of the car. Another fuse 17 is placed in the trolley branch 6 between the master switch 18 and the switch 5 controlled by the governor 4.

In Fig. 2 a valve 13a is employed, which is controlled by a solenoid and a compression spring. Consequently the air pipe section 12 is dispensed with.

While the drainage valves embodying the present invention are shown as being connected to the main reservoir of a fluid pressure system, it is evident that the valves could be employed to drain the liquid from any other part of the system in which it might accumulate.

Referring to Fig. 3, the details of the drainage valve, such as that of Fig. 2, are shown therein. The valve, connected to the main reservoir 3, comprises a valve casing 19 having an inlet member 20 extending within the reservoir 3 at the bottom thereof. The lower portion of the inlet member 20 is adapted to be threaded into the bottom of the reservoir as it is there that liquid will collect. In order that the casing 19 may be detached from the inlet member 20 without disturbing the latter, the casing is threaded at 21 to the inlet member. Apertures 22 are provided in the sides of the inlet member 20 adjacent the bottom of the reservoir so that the liquid which collects in the reservoir may drain into the inlet member 20. The valve stem 23 has an enlarged portion adjacent the lower end and extends through the inlet member 20 and the casing 19. The stem is preferably formed with a longitudinally extending central opening 25 in the enlarged portion with apertures 26 and 27 leading from the opening 25 to the outer side of the valve stem 23. When the drainage valve is in the position shown in Fig. 3 with the apertures 22 and 26 in registration, which will hereinafter be described as the open position, the liquid in the bottom of the reservoir 3 will enter the opening 25 in the valve stem through the apertures 22 and 26 and will flow down through opening 25 and out through the apertures 27 into the valve casing 19. When in open position, the lower end 28 of the valve stem fits tightly into the outlet 29 in the bottom of the casing 19. The valve stem 23 is formed with a reduced portion 30 near the lower end which is smaller than outlet 29. Thus, when the valve stem is moved downwardly so that the apertures 26 are closed by the walls of the lower end of the inlet member 20 and are no longer in registration with apertures 22, thereby preventing any further escape of fluid from the reservoir, the reduced portion 30 is within outlet 29, thereby allowing the water which has accumulated in the valve casing 19 to escape through the outlet 29.

A collar 31 is secured to the valve stem 23 within the inlet member over which collar a shoulder portion 32 is positioned. A spring 33 or any other suitable resilient means may be positioned between the top 34 of the inlet member 20 and the shoulder portion 32 which tends to hold the valve stem 23 down in closed position. An opening 34a is provided in the top 34 which prevents any increase or decrease in pressure within the space between the top 34 and the shoulder portion 32 when the valve stem is moved up and down to operate the valve.

A solenoid 35 contained within the casing 36 which is threaded into the top of the reservoir 3 is secured to the upper side of the reservoir.

Attached to the upper end of the stem 23 by a joint preferably of universal type, is a plunger 24 of iron or other suitable material which is adapted to be acted upon by the solenoid 35. The universal joint prevents binding of the plunger 24 or valve stem 23. When current is passed through the solenoid, the plunger is pulled upward into the position shown in Fig. 3, thereby opening the valve, and when the current is shut off, the spring 33 closes the valve by closing

the inlet and opening the outlet. The solenoid is preferably connected to the wire 14 supplying current to the compressor 1. Thus, every time the compressor is operated, the solenoid opens the valve and allows the liquid to drain down into the valve casing 19.

A heating element 37 is positioned within the valve casing to prevent freezing of the liquid therein in cold weather. The heating element 37 is shown as connected in series with the solenoid 35 but it may be equally well connected in parallel if greater current is desired. With this arrangement, current flows through the heating element whenever the compressor is operated. As the greatest condensation takes place when the compressor is operated and the valve is in open position, as shown in Fig. 3, at the time, the liquid drains immediately into the valve casing where the heating element which is also on at the same time, prevents the liquid from freezing.

The form of drainage valve shown in Fig. 4 is controlled by a solenoid and by pressure, but instead of positioning the solenoid at the upper side of the reservoir 3, as shown in Fig. 3, the solenoid is positioned within the upper portion of the valve casing 19 and is set off from the interior of the valve by the hollow annular casing 36. The inlet member 20 is substantially the same as the inlet member shown in Fig. 3, extending within the reservoir 3 and having apertures 22 in the sides thereof. The upper valve member 38 when in closed position seats in the valve seat 39 formed in the inlet member 20 below the apertures 22.

The valve stem 23a, which is formed with a reduced portion 30, is made solid, the lower end below the joint 40 being preferably formed of iron so as to act as a plunger for the solenoid 35 to control the actuation of the valve stem 23a. A piston 41 is connected to the valve stem 23a and is enclosed within the piston cylinder 42 which is connected to the pressure pipe 12 by an opening 43. An opening 42a leads from the lower end of the piston cylinder 42 to the outer air so that the pressure below the piston will remain at atmospheric pressure at all times. A heater 37 is also provided in this form of valve, a plug 44 being threaded into the bottom of the casing 19 which may be removed to permit the insertion or removal of the heating element 37.

With this form of valve, when the valve stem is raised by action of the solenoid so that the upper valve member 38 is above the apertures 22, the liquid from the reservoir may drain from the reservoir through the inlet opening 45 into the chamber 46 in the upper portion of the valve casing. Slots 47 connect the valve chamber 46 with the lower valve chamber 48 so that the liquid may drain from the chamber 46 down into the bottom of the chamber 48. With the valve stem in raised position, the reduced portion 30 does not coincide with the outlet 29 which therefore remains closed. As the pressure pipe 12 is connected to the straight air application pipe 10, whenever the brakes are set by operation of the motorman's valve 8, pressure is forced through the opening 43 into the piston cylinder 42 above the piston 41, thus forcing the valve stem into closed position, as shown in Fig. 4. As soon as the brakes are released, the pressure escapes from the piston cylinder 42 through the opening 43 and the pipe 12 and when current is supplied to the solenoid, the valve is again raised to open position. By this arrangement, the liquid in the

bottom of the reservoir is frequently permitted to drain into the valve casing where, due to the frequent application of the brakes, it escapes through the outlet 29.

5 The drainage valve shown in Fig. 5 is provided with a hollow stem 23b and apertures 26 and 27 leading from the opening 25 to the outer side of the valve stem. Apertures 22 are likewise provided in the side of the inlet member 20 which, 10 when the valve is in open position as shown in Fig. 5, register with the apertures 26 to permit the liquid to flow from the reservoir through the apertures 26 down through the central opening 25 and out through the apertures 27 into the lower portion of the valve casing 19. A cap 49, having a hole 49a therein, is threaded onto the upper end of the valve stem 23 above the apertures 26 and serves to guide the valve stem 23 within 15 the inlet member 20.

20 An air-tight partition 50 is provided in the valve casing 19 so as to prevent any leakage of pressure from the chamber 51 above the partition into the chamber 52 formed below the same. Heaters 37 which may be in the form of a ring are preferably 25 provided in this partition. A piston 53 is attached to the valve stem 23b above the partition 50 and a spring or other resilient member 54 is positioned between the top of the piston 53 and the top of the valve casing 19, which tends to 30 urge the valve stem downwardly into closed position. An aperture 55 connects the interior of the chamber 51 to the air pressure line 12 so that whenever the brakes are applied pressure is forced into the chamber 51, thereby pushing the piston 53 upwardly to open the valve. As soon as the pressure is released from the brake cylinders 9, the spring, pushing against the piston, urges the valve stem downwardly into closed position so that the water which has drained from the reservoir into the chamber 52 may escape around the reduced portion 30 of the valve stem through 35 the outlet 29.

The drainage valve shown in Fig. 6 is controlled 40 by a solenoid, a piston operated by pressure, and a spring. The solenoid 35 is positioned in the upper portion of the valve casing 19 and is separated from the lower portion of the valve casing by an air-tight partition 56. A hollow piston 57 is 45 provided near the lower end of the valve stem 23c and is in communication with the central opening 25 in the valve stem. An upper valve member 58 is threaded onto the upper end of the valve stem 23c and secured in place by a screw 58a. When in closed position, as shown in Fig. 6, the 50 valve member 58 is below the apertures 22 of the inlet member 20.

An aperture 59 in the lower end of the valve stem, which in this form is made hollow substantially throughout its length, registers with the 55 apertures 60 which serve as outlet openings. When in open position, the apertures 26 adjacent the upper end of the valve stem 23 register with the openings 22, allowing the liquid in the reservoir to flow down through the opening 25 into the lower end of the valve stem 23 and the hollow piston 57. When the valve is then moved to closed position, the apertures 59 register with the apertures 60 and the liquid flows out of the stem and the piston cylinder in which it collected. 60 Aperture 55 communicates with the pressure line 12 and pressure is forced into the lower portion of the casing 19 above the piston 57 whenever the brakes are applied, thus forcing the valve stem downwardly into closed position. The weight of 65 the water in the piston and valve stem tends to

move the valve stem to closed position. A spring 61 may be positioned between the partition 56 and the top of the piston 57 to aid in urging the piston to closed position. The solenoid 35, when current is passed therethrough, pulls the valve stem upwardly to open position. A cap 62 is threaded on the lower end of the valve stem so that in case the passageway through the stem 23c becomes clogged, the cap may be removed and the passage cleared without the necessity of dismantling the drainage valve. Also the lower end 10 63 of the casing 19 containing the outlet 60 is threaded onto the remainder of the valve casing and may be removed if it is desirable to do so without requiring removal of the drainage valve. 15 A heating element 37 is also positioned within the valve casing and may be inserted through the opening 64 in the bottom of the casing which is closed by a plug 65.

20 Although specific valve members have been shown and described for opening and closing the inlet and outlet, other forms of valves may be employed to accomplish the same result.

25 While I have shown and described various embodiments of the present invention, it will be apparent to those skilled in the art that various modifications thereof may be made without departing from the spirit and scope of this invention and therefore I wish to be limited only by the prior art and the scope of the appended claims. 30

I claim:—

1. The combination with a fluid pressure system having a compressed air reservoir, a compressor for supplying air to said reservoir, a source of electrical energy, and means intermittently acting to supply electrical energy to operate said compressor, of a drainage valve connected to said system comprising a casing having an inlet in communication with the interior of said system and an outlet, valve members arranged to open and close said inlet and said outlet alternately, means for operating said valve members whereby liquid may be drained from said system with substantially no reduction of pressure therein, and an electrical heating element positioned within said casing, said heating element being connected to said source of electrical energy whereby whenever said compressor is operated electrical energy is simultaneously supplied to said heating element. 50

2. A drainage valve adapted to be connected to a fluid pressure system having a main reservoir comprising a casing having an inlet extending into said reservoir in communication with said pressure system and an outlet, a valve stem having valve members thereon for opening and closing said inlet and said outlet alternately, and means for operating said valve stem to open and close said inlet and said outlet whereby liquid may be drained from said system with substantially no reduction of pressure therein, said valve stem having a longitudinal opening therein through which said liquid flows in passing from said inlet to said outlet. 60

3. The combination with a compressed air 65 brake system having an electrically operated compressor of a drainage valve comprising a casing having an inlet in communication with said pressure system and an outlet, valve members movable in unison for opening and closing said 70 inlet and said outlet alternately, a solenoid electrically connected to the compressor wiring circuit, means controlled by said solenoid for moving said valve members in one direction whenever said compressor is operated and means controlled 75

by the pressure in said system for moving said valves in the opposite direction upon application of the brakes.

4. A drainage valve adapted to be connected 5 to a fluid pressure system having a main reservoir comprising a casing having an outlet aperture in the lower portion thereof, a chamber extending from said casing and communicating therewith for insertion into said reservoir, said 10 chamber having an inlet aperture whereby liquid in said system may enter said chamber directly and flow down into said casing, a valve stem having valve members thereon for opening and closing said apertures alternately, and means for 15 operating said valve stem to open and close said inlet and said outlet whereby liquid may be drained from said system with substantially no reduction of pressure therein, said valve stem having a longitudinal opening therein through 20 which said liquid flows in passing from said inlet to said outlet.
5. The combination with a fluid pressure system having a compressed air reservoir, a compressor for supplying air to said reservoir, a 25 source of electrical energy, and means intermittently acting to supply electrical energy to operate said compressor, of a drainage valve connected to said system comprising a casing having an outlet aperture in the lower portion thereof, 30 a chamber extending from said casing and communicating therewith for insertion into a portion of a fluid pressure system, said chamber having an inlet aperture whereby liquid in said system may enter said chamber directly and flow down into 35 said casing, valve means arranged to open one aperture and close the other alternately, means for opening and closing said apertures

whereby liquid may be drained from said system with substantially no reduction of pressure therein, and an electrical heating element positioned within said casing, said heating element being connected to said source of electrical energy whereby whenever said compressor is operated electrical energy is simultaneously supplied to said heating element.

6. The combination with a fluid pressure system having a compressed air reservoir, a compressor for supplying air to said reservoir, a source of electrical energy, and means intermittently acting to supply electrical energy to operate said compressor, of a drainage valve connected to said system comprising a casing having an outlet aperture in the lower portion thereof, 10 a chamber extending from said casing and communicating therewith for insertion into a portion of said fluid pressure system, said chamber having an inlet aperture, a valve stem having 15 valve members thereon for opening and closing said apertures alternately, said valve stem having a longitudinal opening therein through which liquid may flow in passing from said inlet to said outlet, whereby liquid in said system may enter 20 said chamber directly and flow down into said casing, means for operating said valve stem to open and close said inlet and said outlet whereby liquid may be drained from said system with substantially no reduction of pressure therein, and 25 an electrical heating element positioned within said casing, said heating element being connected to said source of electrical energy whereby whenever said compressor is operated electrical energy is simultaneously supplied to said heating element.

EDWARD W. ANGER.
